UNITED STATES PATENT OFFICE.

WALTER F. ROGERS, OF OAK PARK, ILLINOIS.

DESIGN FOR A STOVE.

46,582.

Specification for Design.

Patented Oct. 20, 1914.

Application filed July 10, 1914. Serial No. 850,267. Term of patent 7 years.

To all whom it may concern:

Be it known that I, WALTER F. ROGERS, a citizen of the United States, residing at Oak Park, in the county of Cook and State of Illinois, have invented a new, original, and ornamental Design for Stoves, of which the following is a full, clear, and exact description, reference being had to the accompanying drawing, forming a part hereof.

In the drawings: Figure 1 is a perspective view of a stove embodying my new design. Fig. 2 is a plan view of the same.

What I claim as new is—

The ornamental design for a stove, as shown.

In witness whereof, I have hereunto set my hand this 27th day of June, 1914.

WALTER F. ROGERS.
